CONTAINER AND CLOSURE THEREFOR

Eugene Jacob, Trenton, N. J.

Application April 6, 1935, Serial No. 15,046

5 Claims. (Cl. 215—7)

My invention relates to bottles and receptacles and to closures therefor. In particular my invention relates to constructions which render it impossible to remove the closure without mutilating the same whereby an indication is given that the receptacle has been opened.

Constructions are known wherein the closure or the container or both are so formed that the closure must be broken in order that the contents may be removed. However, such devices are usually either complicated and expensive or are constructed so that the closure is completely destroyed when removed and it therefore cannot thereafter be used to preserve the contents of the receptacle.

In accordance with my invention these difficulties and disadvantages of the prior art are overcome and simple and inexpensive closures and containers are provided wherein the closure is mutilated upon removal but is not destroyed. With this construction the closure can be used in the usual manner to preserve the contents of the container but cannot be reused without giving evidence that the container has been opened.

One of the objects of my invention is to provide container and closure constructions which prevent the removal of the closure without mutilation thereof while the closure retains its usefulness for preserving the contents of the container.

Another object of my invention is to provide a simple and inexpensive form of container and closure of the type which cannot be opened without mutilating the closure.

A further object of my invention is to provide a novel type of closure and retaining means therefor.

These and other objects and features of my invention will appear from the following description thereof in which reference is made to the accompanying figures of the drawing illustrating typical constructions embodying my invention.

In the drawing:

Fig. 1 is a perspective of a form of bottle and closure with a portion of the closure broken away to disclose the invention more clearly.

Fig. 2 is a horizontal sectional view of the neck of the container illustrated in Fig. 1 with retaining means in place thereon.

Fig. 3 is a horizontal sectional view similar to Fig. 2 with the closure in place.

Fig. 4 is a view similar to Fig. 3 illustrating the manner in which the closure is mutilated.

Figs. 5 and 6 are sectional views similar to Figs.

3 and 4 respectively of another alternative form of construction embodying my invention, and

Fig. 7 is a perspective of a further alternative form of container and closure embodying my invention.

In that form of my invention chosen for purposes of illustration in Figs. 1 to 4 of the drawing I have shown a bottle or other receptacle 2 having a neck 4 provided with a thread 6 for receiving and retaining a closure 8 for the container. Below the thread 6 a collar 10 is provided which has a recess 12 therein formed at one end with an abutment 14 and on the opposite end with a sloping portion 16 of gradually decreasing depth.

Within the recess 12 is located a locking member 18 which preferably is formed of spring metal or similar material and extends more than half way around the neck so as to retain itself within the recess by the resiliency thereof. This construction of the locking member is simple and inexpensive to produce and employ and may be applied when shipping the empty containers or before filling the same so that the closure may thereafter be applied, by machine or otherwise in the usual manner without presenting any difficulty because of the presence of the locking member.

The locking member is formed on that end thereof adjacent the abutment 14 with a projection 20 which as shown in Fig. 2 normally projects outwardly from the recess beyond the surface of the collar 10. However, as shown in Fig. 3 the end of the locking member is flexed inwardly into a depression 22 when the cover 8 is in place and during the application thereof so that it does not interfere with the operation of applying the closure. The opposite end of the locking member 12 terminates short of the sloping portion 16 of the recess and normally lies below the outer surface of the collar 10.

The upper portion 22 of the closure 8 is formed with an internal thread and may be reinforced by projections 24 or the like or may be made of suitable thickness to resist breaking thereof. That portion of the closure which extends downwardly about the collar 10 serves as a skirt 26 which covers and conceals the recess 12 and the locking member 18 therein when the closure is seated. The skirt 26 preferably is formed integral with or secured to the upper portion of the closure by a weakened portion 28. Strengthening projections 30 may also be spaced at intervals about the periphery of the skirt to insure breaking thereof at the weakened portion 28.

The strengthening projections also serve to prevent breaking away of the entire skirt in a way which while changing the appearance of the closure would leave a neat appearing closure that 5 might not apprise the purchaser that the closure had been previously removed.

In using the construction described the closure is applied by rotation thereof in a clockwise direction as seen in Fig. 3 whereby the threads 10 on the closure and container engage and the skirt 26 is moved downwardly to cover the recess 12 and locking member 18 to conceal the same. The closure rotates freely in a clockwise direction due to the fact that the projecting 15 portion 20 of the locking member faces in the direction of rotation of the adjacent inner surface of the skirt and is therefore flexed inwardly into the depression 22. Furthermore since the projecting portion 20 is adjacent the abutment 14 20 at the end of the recess 12 the locking member cannot be carried with the closure in applying the same.

When the closure is removed by rotation thereof in a counter-clockwise direction as seen in Fig. 3 the projecting portion 20 of the locking member which tends to move outwardly engages the inner surface of the skirt 26 and either imbeds itself in the closure or frictionally engages the same so that the locking member is 25 moved with the closure in a counter-clockwise direction. The opposite end of the locking member then slides upwardly along the inclined surface of the recess 12 and is wedged into the space between the skirt 26 and the collar 10. 30 Further rotation of the closure in a counter-clockwise direction is therefore resisted. However on forcible rotation of the closure to remove the same the locking member is moved with the closure into the position shown in Fig. 4. When so moved the skirt is expanded and 35 since it is secured to the upper portion of the closure by the weakened portion 28 it is broken away below the thread. Furthermore the reinforcements 30 cause the skirt itself to be broken. 40 The closure is thus mutilated without destroying or injuring the upper portion thereof. The closure may thereafter be applied and removed as desired so that the contents of the container 45 may be preserved by the use of the same closure but the closure cannot again be used without giving evidence of the fact that the container 50 has previously been opened. It will thus be apparent that the construction provided is simple and inexpensive to manufacture and employ and 55 at the same time serves to prevent reuse of the closure in an unauthorized manner.

In that form of my invention illustrated in Figs. 5 and 6 the recess 12 is similar to that used in the form of my invention shown in Figs. 1 to 4. 60 However, in this case the locking member is formed with a projection 38 on that end thereof adjacent the sloping portion 16 of the recess and a depression 40 is located adjacent the projection 38.

65 The closure may be applied as in the previous forms of my invention by rotation in a clockwise direction as seen in Fig. 5 during which operation the projection 38 is forced inwardly into the recess 40 adjacent the sloping portion of the recess. When the closure is rotated in a counter-clockwise direction to remove the same projection 38 engages the inner surface of the skirt 26 of the closure so that the locking member moves with the closure up the sloping end 16 of 70 the recess toward the restricted space between 75

the skirt 26 and the collar 10. Continued rotation in a counter-clockwise direction is therefore resisted whereas on forcible rotation to remove the closure the skirt is expanded causing the same to be broken away below the threaded portion of the closure. 5

The construction shown in Fig. 7 differs from those previously described in that the recess 42 in which the locking member 18 is located is in alignment with the outer diameter of the thread. 10 The closure is weakened by reducing the thickness thereof above or adjacent the locking member. The diameter of the closure may therefore be uniform throughout or may be smaller adjacent the lower portion thereof than throughout 15 the upper, internally threaded portion. While the weakened portion may be a continuous groove located at or above the locking member I prefer to employ spaced strengthening elements 44 in a skirt which is thinner than the upper portion of the closure. In this way the skirt is caused to break in an irregular and therefore very apparent manner. The type of locking member and recess used may be any of those heretofore described or capable of functioning 20 in a similar manner. 25

In each of the forms of my invention described rotation of the closure in removing the same causes the locking member to be rotated with the closure so that it is moved out of the recess 30 into an expanded position forcing the skirt outwardly until it is broken at the weakened portion leaving the upper threaded portion of the closure uninjured. The desired effect is attained very readily when using closures formed of 35 moulded plastic compositions and while this construction is preferred the closure may, if desired, be made of metal or of any other suitable material capable of being readily broken or permanently deformed in removing the closure. 40

While I have illustrated and described certain preferred forms of my invention it will of course be evident that numerous changes and modifications may be made in the form and arrangement of the element thereof. Therefore it should be 45 understood that the forms of my invention herein disclosed have been given by way of illustration and are not intended to limit the scope thereof. 50

What I claim as my invention is:

1. The combination comprising a container having a circular neck threaded externally and formed with a circumferential recess below the thread, a locking member carried by the container normally located in said recess and slideable circumferentially of the container to an expanded position in which a portion thereof extends out of said recess, and a closure threaded internally engaging the thread on the neck of the container and formed with a skirt extending below said thread and about the locking member in said recess and closely adjacent said circular neck, said locking member and skirt having co-operating elements serving to move the locking member with the closure to said expanded position in which the locking member is wedged between said closure and a circular portion of the container to break said skirt outwardly upon rotation of the closure to remove the same. 60

2. The combination comprising a container having a circular neck threaded externally and formed with a circumferential recess below the thread, a locking member carried by the container normally located in said recess and co-operating with an outwardly extending portion 70 75

of the neck at the end of said recess upon sliding movement of said member circumferentially of the container to expand the same and a closure threaded internally engaging the thread 5 on the neck of the container and formed with a skirt extending below said thread and about the locking member in said recess and closely adjacent said circular neck, said locking member and skirt having cooperating elements serving 10 to move the locking member with the closure to said expanded position in which the locking member is wedged between said closure and a circular portion of the neck of the container to break said skirt outwardly upon rotation of the 15 closure to remove the same.

3. The combination comprising a container having a circular neck threaded externally and formed with a circumferential recess below the thread, a resilient locking member carried by 20 the container and movable circumferentially of the container extending more than half way about the circumference of said neck and normally retained in said recess by the resiliency thereof and a closure threaded internally engaging the thread on the neck of the container and formed with a skirt extending below said thread and about the locking member in said recess and closely adjacent said circular neck, said locking member and skirt having cooperating 25 elements serving to move the locking member with the closure to said expanded position in which the locking member is wedged between said closure and a circular portion of the neck of the container to break said skirt outwardly upon rotation of the closure to remove the same. 30

4. The combination comprising a container having a circular neck threaded externally and formed with a circumferential recess below the thread extending more than half way about 35 the circumference of the neck, a resilient locking member carried by the container and movable

circumferentially of the container located in said recess and extending more than half way about the neck and normally held therein by the resiliency of said member, the end of the locking member cooperating with an end of the recess on 5 movement of the member to expand the same and a closure threaded internally engaging the thread on the neck of the container and formed with a skirt extending below said thread and about the locking member in said recess, said 10 locking member and skirt having cooperating elements serving to move the locking member with the closure to said expanded position in which the locking member is wedged between said closure and a circular portion of the neck of the 15 container to break said skirt outwardly upon rotation of the closure to remove the same.

5. In combination with a container having an external thread thereon, an internally threaded container closure of the cap type adapted to 20 engage the external thread on the container and to normally completely cover the container opening, said closure having an integral peripheral skirt portion below the thread constituting an externally visible, readily breakable indicator, 25 said skirt portion and container presenting surfaces defining a recess which is deeper in one part than in another and a normally concealed device positioned in said recess and located between said container and the skirt portion of 30 the closure, said device being movable into the deep part of said recess to a retracted position permitting free rotation of the closure on rotation thereof in applying the same to the container and being movable into the shallower 35 part of said recess and into wedging relation with said skirt portion and container to break said skirt outwardly on rotation of the closure to remove the same from the container.

EUGENE JACOB.
